(57) **CLAIM**

The ornamental design for a seed and plant bag, as shown and described.

DESCRIPTION

FIG. 1 shows a front perspective view of a seed and plant bag showing my new design in a closed state.

FIG. 2 is a front elevation view thereof.

FIG. 3 is a rear elevation view thereof.

FIG. 4 is a left elevation view thereof.

FIG. 5 is a right elevation view thereof.

FIG. 6 is a top plan view thereof.

FIG. 7 is a bottom plan view thereof.

FIG. 8 is a front perspective view thereof in an open state.

FIG. 9 is a front elevation view thereof.

FIG. 10 is a rear elevation view thereof.

FIG. 11 is a left elevation view thereof.

FIG. 12 is a right elevation view thereof.

FIG. 13 is a top plan view thereof.

FIG. 14 is a bottom plan view thereof; and,

FIG. 15 is a front perspective view thereof.

The very fine stippling on the bottom one third of the bag denote that portion of the bag is opaque. The cross-hatching showing sealed edges is understood to be distributed uniformly around the edges on three sides of the claimed design even though it is shown intermittently on part of the edges. The broken lines in the drawings are included to show portions of the bag and subject matter that forms no part of the claimed design.
